Primary Examiner — Elizabeth Albert

(74) Attorney, Agent, or Firm — Dinsmore & Shohl LLP;
Douglas McEvoy(57) **CLAIM**

The ornamental design for a planting support kit, as shown and described.

DESCRIPTION

FIG. 1 is an exploded perspective view of the planting support kit showing my new design;
 FIG. 2 is a front plan view of FIG. 1;
 FIG. 3 is a top plan view of FIGS. 1-2;
 FIG. 4 is a ninety degree rotated right side plan view of FIG. 2, a corresponding left side plan view being a mirror image thereof; and,
 FIG. 5 is a bottom plan view of FIGS. 1-4.

1 Claim, 5 Drawing Sheets(56)
